UNITED STATES PATENT OFFICE.

JACOB J. BYERS, OF CAMERON, MISSOURI, ASSIGNOR OF ONE-HALF TO THE NATIONAL MALLEABLE CASTINGS COMPANY, OF CLEVELAND, OHIO.

DRAFT-RIGGING.

SPECIFICATION forming part of Letters Patent No. 673,419, dated May 7, 1901.

Application filed April 21, 1900. Serial No. 13,744. (No model.)

To all whom it may concern:

Be it known that I, JACOB J. BYERS, of Cameron, in the county of Clinton and State of Missouri, have invented a new and useful 5 Improvement in Draft-Rigging, of which the following is a full, clear, and exact description, reference being had to the accompanying drawings, forming part of this specification, in which—

10 Figure 1 is a side elevation showing the upper part of the figure in central longitudinal section. Fig. 2 is a sectional plan view on the lines II II and II^a II^a of Fig. 1. Fig. 3 is an end view, the left-hand portion of which 15 is in vertical section on the line III III and the remainder in vertical section on the line III^a III^a. Fig. 4 is an elevation of the inner side of the follower. Fig. 5 is a side view of the follower. Fig. 6 is a side elevation of a 20 modified construction. Fig. 7 is a bottom plan view of Fig. 6, partly in section and showing the bottom plate removed. Fig. 8 is an end elevation showing the draw-bar shank in section. Fig. 9 is an end view of the stop. 25 Fig. 10 is a top plan view of a modified construction, showing the draft-arms integral with the part of the rigging which contains the springs. Fig. 11 is a side elevation of Fig. 10. Fig. 12 is a cross-section on the line 30 XII XII of Fig. 10.

In Figs. 1, 2, and 3, 2 represents the shank of a draw-bar, and 3 represents a pocket which contains the springs of the draft-rigging and is set between draft-timbers, (not 35 shown,) to which it is affixed by bolts 4. The pocket may be cast in a single piece and is provided with horizontal lugs 5, which extend across the pocket, above and below, and constitute abutments for the followers 6 40 and 6', which are set in the pocket. The pocket and lugs are suitably braced by metal ribs or flanges, as shown. 7 are the springs, placed, preferably, one above the other between the followers, and to hold them in place, as well 45 as to limit the approach of the followers, I may provide the latter with projecting stops 8, which extend from such followers between the springs. The draw-bar shank 2 is connected with the rear follower 6' by a yoke 2', 50 which is fixed to the draw-bar by riveting or otherwise and extends within the pocket, be-

tween the lugs and around the rear follower, as shown. The pocket is open at the bottom, so that the follower-plates and springs may be removed freely from within the yoke in a 55 vertical direction without the necessity of disengaging the yoke from the draw-bar, since the follower-plates are not connected with the draw-bar otherwise than by being placed between the sides of the yoke. This removal 60 is made possible by taking off a cap-plate 9, which closes the opening at the bottom of the pocket and is secured by bolts 9^a, and the follower-plates can then be pried out by means of a tool applied to toothed recesses 10, formed 65 in the edges of the follower-plates. To facilitate the insertion of the follower-plates and springs, I prefer to bevel the ends of the follower-plates, as shown at b b. The pocket is preferably made alike at both ends, as shown 70 in Figs. 1 to 3, with an opening c at each end for the passage of the draw-bar shank, so that it is reversible and can be turned in either direction.

In the figures on the second sheet of the 75 drawings I show modifications of my invention, in which the draw-bar shank is attached to the yoke 2' by a rivet-key 11, which may be passed through the transverse slot ordinarily formed in draw-bars for the attachment of 80 the so-called "American" continuous draft-rods and through slots in the arms of the yoke and is upset at the ends, as shown. In these figures also I show a stop-piece 12, made separate from the follower-plates and interposed between the springs, performing the same function as is performed by the projections from the follower-plates shown in Figs. 1 and 4.

In Figs. 10 to 12, on the third and fourth 90 sheets of the drawings, I show my improvement applied to use with the American continuous system, in which the draw-bars at the opposite ends of the car are connected by transverse keys and longitudinal rods, and to 95 this construction I intend to make specific claim in addition to my generic claims. In these figures I show the rigging provided with metal draft-arms 13, which may be cast integrally with each other and with the pocket 100 above described and which are abutted against the ends of the draft-timbers 14, of

which they form a continuation and to which they are secured by bolts 15. The draft-arms are also secured to the sills above by bolts 16 and may be connected at the top and bottom 5 as well as at the rear by integral webs or plates, it being necessary only to leave an opening at the bottom, through which the springs and followers may be removed, and to close said opening by a removable plate or 10 cap 9'. The draw-bar is connected to the arms of the yoke by a key 17, which extends through the usual slot in the draw-bar, through slots in the arms of the yoke, which are preferably doubled, so as to give a better 15 bearing for the key, and through slots in the draft-arms and is adapted to be connected with the draft-rods 19 of the continuous system. In addition to the stop 12 which I show in these figures I also show as an alternate 20 construction stops 18, either hollow or solid, which may be set axially in the springs between the follower-plates. The draft-arms shown in these figures are preferably strengthened by flanges at the sides and constitute a 25 strong and very desirable construction.

The advantages of my invention will be appreciated by those skilled in the art. The springs arranged one above the other, the pocket having horizontal lugs or abutments 30 for the followers, the free removability of the springs and the followers from below from between the arms of the yoke and from the pocket, and the construction of the draft-arms shown in Fig. 10, together with the 35 other items mentioned in the claims, constitute, severally and in combination, important parts of my invention.

I claim—

1. A draft-rigging having in combination 40 with the draw-bar, a yoke, the arms of which are connected to the sides of the draw-bar, springs arranged one above the other within the yoke, and followers also arranged between the arms of the yoke, said springs and 45 followers being removable from below, independently of the draw-bar; substantially as described.

2. A draft-rigging having a yoke, the arms of which are adapted to be connected to the 50 sides of a draw-bar, springs arranged one above the other between the arms of the yoke, and followers adapted to fit against the ends of both springs, and also contained between the ends of the yoke, said springs and followers being removable from below independently of the draw-bar; substantially as described.

3. A draft-rigging having a pocket, lugs, extending horizontally across the pocket at 60 the upper and lower portions thereof respectively, followers within the pocket which bear against the lugs, and a yoke which ex-

tends within the pocket between the lugs and around the rear follower; substantially as described.

4. A draft-rigging having a pocket, lugs extending horizontally across the pocket at the upper and lower portions thereof respectively, followers within the pocket which bear against the lugs, a yoke which extends within 65 the pocket between the lugs and around the rear follower, and braces connected with the lugs and pocket; substantially as described.

5. A draft-rigging having a yoke open at the bottom and having a spring and followers 70 arranged between the arms of the yoke, and a pocket within which the yoke extends and which is also open at the bottom to permit removal of the spring and followers independently of the draw-bar; substantially as described.

6. A draft-rigging having a yoke open at the bottom and having a spring and followers arranged between the arms of the yoke, a 75 pocket which contains the yoke and is also open at the bottom to permit removal of the spring and followers, and a detachable closure for the opening in the pocket; substantially as described.

7. A draft-rigging having, in combination 80 with the draw-bar and spring mechanism, a yoke the arms of which are connected to the sides of the draw-bar, a pocket within which the yoke extends, and a key which extends horizontally through the draw-bar and yoke, 85 and through slots in the walls of the pocket; substantially as described.

8. A draft-rigging having springs set one above the other, and a follower engaging the 90 ends of both springs and having at the middle a stop projection which separates the springs; substantially as described.

9. A draft-rigging having springs set vertically one above the other, and a single pocket having at opposite ends horizontal lugs at 95 the top and bottom of the pockets, followers in the pocket set between the lugs, and adapted to receive a spring between them; and a yoke which extends within the pocket between the lugs; substantially as described.

10. A draft-rigging having springs arranged vertically, one above the other, followers, a yoke between the sides of which the springs and followers are set, said springs and followers being removable vertically from below independently of the draw-bar; substantially as described.

In testimony whereof I have hereunto set my hand this 6th day of April, 1900.

JACOB J. BYERS.
